UNITED STATES PATENT OFFICE.

LOUIS D. GENTZLER, OF PORTIS, KANSAS, ASSIGNOR TO CRESCENT
MFGR. CO., OF KANSAS CITY, MISSOURI.

MORTAR-MIXER.

No. 845,942.

Specification of Letters Patent.

Patented March 5, 1907.

Application filed December 15, 1905. Serial No. 291,887.

To all whom it may concern:

Be it known that I, LOUIS D. GENTZLER, a citizen of the United States, residing at Portis, in the county of Osborne and State of Kansas, have invented new and useful Improvements in Mortar-Mixers, of which the following is a specification.

This invention is a machine for mixing mortar, cement, and the like; and it is characterized particularly by simplicity and cheapness of construction and by improvements with respect to the means for feeding the sand, cement, or other material to a mixing-drum and also with respect to the means 15 for supporting and driving said drum.

In the accompanying drawings, Figure 1 is a perspective view of the invention. Fig. 2 is a top plan view. Fig. 3 is a central longitudinal section. Fig. 4 is an end elevation.

Referring specifically to the drawings, 6 indicates the main sills, upon which the other parts are supported.

7 indicates one hopper, and 8 the other—say for sand and cement, respectively. These 25 hoppers are arranged side by side and connect, respectively, with the casings 10 of a pair of elevators, which are arranged side by side and contain endless belts 11, carrying buckets 12. Spouts 13 at the top of the elevators discharge into a hopper 15 at the head of a mixing-drum 16, which comprises a metal cylinder containing an axial shaft 17 and paddles or beaters 18, arranged spirally around the same. This cylinder is suspended between two standards 19, which are mounted at their lower ends upon the sills 6 by means of a strap 20, which is wound around a winding-shaft 21, journaled in the top of the standards. This construction enables the drum to be raised or lowered to 35 vary its inclination. The mixer-shaft 17 is supported at its ends by cross-bars 22, which extend across the ends of the mixing-cylinder. The main drive-shaft 23 is journaled in bearings at the head of the uprights 24, which serve also to support the casings of the elevators. This shaft extends through holes in arms 25, which project from the head of the mixing-drum, whereby a pivotal connection 40 of the drum with the shaft is formed to allow the variation of inclination above referred to. At its upper end the shaft 17 has a bevel-gear 26, which meshes with a bevel-gear 27 on the drive-shaft 23. The drive-shaft

also carries pulleys 28, which are connected by belts 29 with pulleys 30 on the shafts, over which the endless belt conveyers run. The relative size of these pulleys controls the proportions of the respective materials delivered to the mixing-drum. 55

To prevent clogging of the sand or other material in the feed-hoppers 7 and 8, reciprocating feeders 31 are employed, consisting of bars having blades which work to and fro in the hoppers and stir the sand or cement, 60 so that it will feed to the elevators. These bars are connected to eccentrics 32, which are mounted on the shafts 33, which carry the sprockets 34 at the lower end of the elevators. As the wheel rotates the feeders are 65 moved back and forth, with the result stated.

Water is fed to the mixing-cylinder through a pipe 35, which terminates in a cap 36, under which the cylinder is provided with a number of perforations and located on the 70 top of the cylinder, near the head thereof, so as to discharge thereinto and spray the water onto the material therein. 75

The ability to vary the inclination of the mixing-cylinder is advantageous in order to 80 regulate the thickness of the mortar or cement, because it has been found that the thickness of the mortar will naturally vary according to the feed and the moisture in the sand. The variation of inclination also enables the intimacy of the mixture to be varied. The relative sizes of the pulleys 28 and 85 30 control the feed of the respective materials. By the substitution of larger or smaller pulleys the feed may be varied as desired. 90

I claim—

In a mixing-machine, the combination of a cylinder having arms projecting at opposite sides from the head end thereof, a shaft extending lengthwise within the cylinder and 95 having paddles, a drive-shaft geared to said shaft and extending horizontally across the head of the cylinder and to which the arms are pivotally connected, and means to raise or lower the other end of the cylinder. loc

In testimony whereof I have signed my name to this specification in the presence of two subscribing witnesses.

LOUIS D. GENTZLER.
